CONTROL CENTER SUPPORT ARM FOR DENTAL CHAIRS

Dwight A. Booth, Portland, Oreg., assignor to
MDT Instrument Company, Gardena, Calif.

Filed Nov. 3, 1973, Ser. No. 412,303

Term of patent 14 years

Int. Cl. D24—01

U.S. Cl. D24—1 B

FIG. 1

FIG. 2

FIG. 1 is a perspective view of a control center support arm for dental chairs, showing my new design; and

FIG. 2 is a perspective view thereof, with the support arm in an alternate position.

The broken lines are shown for illustrative purposes only.

I claim:

The ornamental design for a control center support arm for dental chairs, as shown and described.
